United States Patent Office.

JOHN MARTINO, JACOB BEESLEY, AND JOHN CURRIE, OF PHILADELPHIA, PENNSYLVANIA, ASSIGNORS TO HENRY McCLENEGHAN, OF THE SAME PLACE.

Design No. 3,482, dated May 11, 1869.

DESIGN FOR A COOK'S RANGE.

The Schedule referred to in these Letters Patent and making part of the same.

To all whom it may concern:

Be it known that we, JOHN MARTINO, JACOB BEESLEY, and JOHN CURRIE, of the city of Philadelphia, and State of Pennsylvania, have originated a new Design for a Cooking-Range, of which the following is a clear and exact description: reference being had to the accompanying drawings, making part of this specification.

Figure 1. A, warming-oven door, with oval panel in centre, ornamented with French style pointed moulding, dotted with beads, with French style pod and leaf at each end, and at top and bottom.

Figure 2. B, baking-oven door, of same style as fig. 1, excepting pod and leaf at top and bottom.

Figure 3. C, baking-oven door, of same style as fig. 2.
Figure 4. D, fire-door, of the same style as fig. 3.

What we claim as our invention, and desire to secure by Letters Patent, is—

The design for a cooking-range, as set forth and shown.

JOHN MARTINO. [L. S.]
JACOB BEESLEY. [L. S.]
JOHN CURRIE. [L. S.]
